US0D1051446S

(12) **United States Design Patent** (10) **Patent No.:** **US D1,051,446 S**
(45) **Date of Patent:** **** Nov. 12, 2024**

(54) **FRONT TURN SIGNAL FOR VEHICLES**

(71) Applicant: **Guangzhou Chengguang Future Automotive Lighting Co., Ltd.,**
Guangzhou (CN)

(72) Inventor: **Lanyan Jiang**, Guangzhou (CN)

(73) Assignee: **Guangzhou Chengguang Future Automotive Lighting Co., Ltd.**

(**) Term: **15 Years**

(21) Appl. No.: **29/826,860**

(22) Filed: **Feb. 16, 2022**

(30) **Foreign Application Priority Data**

Jan. 19, 2022 (CN) 202230037205.2

(51) **LOC (14) Cl.** **26-06**

(52) **U.S. Cl.**

USPC **D26/28**

(57) **CLAIM**

The ornamental design for a front turn signal for vehicles, as shown and described.

DESCRIPTION

FIG. 1 is a first perspective view of a front turn signal for vehicles showing my design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines shown in the drawings depict portions of the front turn signal for vehicles that form no part of the claimed design.

1 Claim, 8 Drawing Sheets
